UNITED STATES PATENT OFFICE.

HERMAN H. OSWALD, OF PEMBROKE, BERMUDA.

COMBINED BRUSH AND SHAVING-STICK.

1,244,771.

Specification of Letters Patent. Patented Oct. 30, 1917.

Application filed January 22, 1916. Serial No. 73,555.

To all whom it may concern:

Be it known that I, HERMAN H. OSWALD, a citizen of the United States of America, residing at Pembroke, Bermuda, have invented certain new and useful Improvements in Combined Brushes and Shaving-Sticks, of which the following is a specification, reference being had therein to the accompanying drawing.

10 My invention relates to combination shaving brush and soap stick holders, and has for its object the provision of a simple, convenient and compact article of the above type.

15 Generally stated, the invention consists of a central holder, having the brush and shaving stick projecting from opposite ends thereof, with separate detachable covers for the brush and stick together with simple 20 and efficient means for holding the various parts together in operative relation.

My invention is illustrated in the accompanying drawings in which:

Figure 1 is a longitudinal cross section 25 of the article completely assembled.

Fig. 2 is a front plan view of the same with the covers removed.

Fig. 3 is a similar view of the brush and its mounting, removed.

30 Fig. 4 is a side elevation of the shaving stick and its mounting, removed.

Fig. 5 is a side elevation of the guide shield.

Fig. 6 is a top plan view of Fig. 5.

35 Referring more specifically to the drawing, 1 indicates the central holder member which forms the usual mounting for the shaving brush 2 and is provided at the end opposite the brush with a reduced, threaded

40 projection 3. The shaving stick 4, provided with the usual protective foil wrapper 5, is fixed in the holder-clip 6 by means of a suitably poured compound, such as paraffin, indicated at 7, filling the space between the 45 adjacent surfaces of the clip and the stick.

An annular groove 8 is formed in the stick 4 to afford a positive hold for the filler 7. The holder-clip 6 has an inwardly dished portion 9 threaded at 10 to take the threaded

50 projection 3 of the brush mounting, the diameter of the dished portion being such in relation to the overall diameter of the holder clip, that a flat rim 11 is formed around it to engage the shoulder 12 on the brush mounting. An annular knurled projection 13, is formed on the outer portion

of the stick holder to afford a friction hold in assembling the parts. The outer face of the stick holder is provided with a screw thread 14 below the knurled projection to 60 engage the thread 15 in the stick cover 16. The cover 16, is of course, so proportioned as to receive the shaving stick 4 and is formed with the bottom 17 flat as shown in Fig. 7, this for the purpose of allowing the 65 whole device to be stood vertically on end with the brush upward. The brush is also provided with a cover 18 adapted to fit snugly over the portion 1 with a friction hold. The top of the brush cover is here 70 shown arched, although I may make it flat so as to allow the device to be stood on end with the brush downward, to allow the bristles to drain. This brush cover is, of course, suitably proportioned to contain the 75 brush without undue compression of the bristles, and to facilitate the insertion of the brush in its cover, a guide or shield 19 is provided for compressing the bristles of the brush and guiding them into the cover. 80

While I have here shown the cover 16 held in engagement with the shaving stick holder 6 by means of screw threads, it is obvious that various other holding means may be employed for this purpose, such as a stud 85 and socket snap hold, a bayonet slot connection or the like. The foregoing statement applies also to the connection between the main body portion 1 and the brush cover.

The method of using the combination is as 90 follows:

The brush cover 18 is removed and the brush dipped in water and used to wet the face. The cover 16 is then removed to expose the soap stick 4 and using the central 95 holder member 1 as a handle, the face is rubbed with the end of the soap stick, in the usual manner, after which the cover 16 is replaced, serving thereafter as a handle for the brush and a stand or base by which the 100 brush may be stood vertically during periods of non-use. After use, the brush may be washed and set aside uncovered to dry in the usual manner, or if desired it may be immediately placed in a traveling bag or 105 the like among other articles without injury thereto by replacing the cover 18. In doing this, the shield 19, of celluloid, cloth or other suitable material, is wrapped about the brush and contracted around the bristles 110 to permit both the brush and the shield to be inserted in the cover 18, thus preventing

injury to the bristles. Preferably, the shield 19 is formed of resilient material and shaped to a diameter normally greater than the inside diameter of the brush cover, as shown 5 in Fig. 6, whereby it will tend to press against the sides of the cover away from the bristles remaining in the cover when the brush is subsequently removed.

It is to be noted, that the brush 2 and the 10 central portion 1 which constitutes its mounting, together with cover 18 may be separated from the soap stick with its holder and cover, so that they may be separately packed and still be protected. After the 15 soap has been used up to the level of the edge of the holder 6 the holder may be detached from the brush and replaced by a new, duplicate stick and holder, the stick being made up with the holder. Thus the 20 stick and holder combined, as shown in Fig. 4, constitute a recharge or renewal.

While I have here shown a preferred specific embodiment of my invention, it is to be understood that various changes may be 25 made therein without departing from the spirit of the invention, and all such changes as fairly fall within the scope of the appended claims are contemplated by me.

Having thus described my invention, what 30 I claim and desire to procure in Letters Patent is:

1. In combination, a soap stick, a metal holder or base therefor formed with a central hollow boss or projection with a closed 35 bottom embedded in one end of and rigidly supporting the soap stick, said holder also having a flange projecting beyond the sides of the soap stick, and a cover or shell, detachably fitted to said projecting flange, 40 rounding and inclosing the soap stick but out of contact therewith, said boss or projection having means to receive and retain the head end of a shaving brush projecting oppositely from the soap stick, whereby 45 when the brush and cover are in place, the latter serves as a handle for the former, and when the cover is detached, the soap stick is completely exposed.

2. A shaving brush and soap stick holder 50 comprising a coupling member shaped to form two concentric nested chambers open at opposite ends only, one of the chambers being formed to receive the end of a soap stick, and the other of said chambers being 55 formed to receive and hold the handle of a shaving brush.

3. A holder for a shaving brush and soap stick having a pair of concentric nested

chambers open at opposite ends only, the outer end shaped to receive and hold a stick 60 of soap and the inner end adapted to receive and hold the end of a shaving brush handle in threaded engagement therewith.

4. A shaving stick holder arranged to receive the end of a shaving stick and having 65 a dished portion with a closed bottom extending a short distance within the solid body of the soap stick and adapted to receive the end of the handle of a shaving brush. 70

5. A holder for a shaving brush and soap stick comprising a coupling member shaped to form two chambers one within the other and open at opposite ends only, one of said chambers being arranged to receive and hold a soap stick by one end thereof and the other said chamber being arranged to receive and hold the handle of a shaving brush. 75

6. The combination of a shaving stick and 80 holder therefor comprising a holder member shaped to form two chambers one within the other and open at opposite ends only, the inner chamber being formed to receive and hold the end of a shaving brush handle, 85 a soap stick having one end shaped to fit within said outer chamber spaced from the outer wall thereof and having an annular groove near said end within said outer chamber, the wall of said outer chamber 90 having an annular groove in its inner surface, and a filler occupying the space within the said grooves and between said soap stick and said outer wall to anchor said soap stick in said holder member. 95

7. The combination of a shaving stick and holder therefor comprising a holder member shaped to form two chambers one within the other and open at opposite ends only, the inner chamber being formed to receive 100 and hold the end of a shaving brush handle, a soap stick having one end shaped to fit within said outer chamber spaced from the outer wall thereof and having an annular groove near said end within said outer chamber, the wall of said outer chamber having 105 an annular groove in its inner surface, and a filler occupying the space within the said grooves and between said soap stick and said outer wall to anchor said soap stick in 110 said holder member, together with a casing arranged to inclose said soap stick and engage the outer wall of said outer chamber.

In testimony whereof I affix my signature.

HERMAN H. OSWALD.
